UNITED STATES PATENT OFFICE.

WILLIAM HENRY BARR, OF STEUBENVILLE, OHIO, ASSIGNOR TO ALEXANDER J. BEATTY & SONS, OF SAME PLACE.

DESIGN FOR A JAR.

SPECIFICATION forming part of Design No. 18,225, dated April 3, 1888.

Application filed January 12, 1888. Serial No. 260,582. Term of patent 3½ years.

To all whom it may concern:

Be it known that I, WILLIAM HENRY BARR, a citizen of the United States, residing at Steubenville, in the county of Jefferson and State of Ohio, have invented and produced a new and original Design for Glassware; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This design relates to ornamentation of all kinds of glassware, and for convenience of illustration it is shown in the annexed drawings applied to a jar.

The salient feature of the design is zigzag or waved ribs or bars, which extend from top to bottom of the ware in parallel rows. These ribs or bars are of any contrasting color with the body of the ware of which they form a part.

In the drawings, Figure 1 is a side view of

a jar ornamented with my design, and Fig. 2 a top plan view of the same.

The jar or other article of glassware A is provided with a series of zigzag or waved ribs or bars, B, of contrasting color. These ribs or bars B are parallel with each other and extend around the sides of the jar from the top to the bottom thereof.

Having thus described my invention, what I claim, and desire to secure by Letters Patent, is—

The herein shown and described design for a jar or kindred article of glassware, consisting of vertical parallel zigzag ribs or bars of contrasting color with the body of the jar, and arranged about the sides of the jar and extending from the top to the bottom thereof, substantially as set forth.

In testimony whereof I affix my signature in presence of two witnesses.

WILLIAM HENRY BARR.
